TOOL HOLDER

Floyd C. King, Birmingham, Mich., assignor to
Guardian Trust Company of Detroit, trustee,
Detroit, Mich., a corporation of Michigan

Original application February 11, 1929, Serial No.
339,145. Divided and this application October
29, 1931. Serial No. 571,929

13 Claims. (Cl. 164—118)

This invention relates generally to tool holders and constitutes a division of my Patent Number 1,910,296 which issued May 23, 1933.

One of the essential objects of the invention is to provide a holder wherein a number of tools such as punches and the like may be held in close formation for engagement with the work.

Another object is to provide a holder wherein a plurality of bodies are arranged in superposed or stacked relation and have means such as bores for receiving tool shanks, certain of the bores in the lowermost body being preferably closed by the lower face of the uppermost body whereby the latter constitutes a backing plate for tool shanks received in such bores, and another of the bores in the lowermost body being in registration with a bore in the uppermost body whereby a longer tool shank may be received in both of said bodies.

Another object is to provide a holder wherein means is provided in one of said bodies for holding tool shanks received within the bores in said body, and means is provided in the other of said bodies for holding the tool shank received in both of said bodies.

Another object is to provide a holder wherein the retaining means in both bodies are accessible from the lower faces of the lowermost body.

Other objects, advantages and novel details of construction of this invention will be made more apparent as this description proceeds, especially when considered in connection with the accompanying drawings, wherein:

Figure 1 is a vertical sectional view through a holder embodying my invention and showing the same applied to the base casting of a punch press;

Figure 2 is a top plan view of the lowermost body illustrated in Figure 1;

Figure 3 is a bottom plan view of the lowermost body illustrated in Figure 1;

Figure 4 is a bottom plan view of the uppermost body illustrated in Figure 1;

Figure 5 is a top plan view of the uppermost body illustrated in Figure 1;

Figure 6 is a bottom plan view of a slightly modified form of holder;

Figure 7 is a sectional view taken on the line 7—7 of Figure 6;

Figure 8 is a plan view of the upper body illustrated in Figure 7.

Referring now to the drawings, 1 is the plunger or ram of a punch press and 2 and 3 respectively are cooperating tool receiving bodies of a holder embodying my invention. As shown, the bodies

2 and 3 are arranged in superposed relation and are secured by bolts 4 to the ram 1 of the punch press. The upper body 2 has a single vertical bore 5 that extends therethrough and is closed at its upper end by a hardened backing plate 6 interposed between the body 2 and ram 1, while the lower body 3 has a vertical bore 7 in alignment with the bore 5 and has a series of vertical bores 8 arranged in a circle about said bore 7, preferably concentrically with respect thereto.

Each of the last mentioned bores 8 extends through the lower body 3 and has its upper end closed by the lower face of the upper body. Arranged in another circle, preferably concentric with the bore 7 and the circle of bores 8, are shorter bores 9 that extend downwardly from the upper face of the lower body in substantially parallel relation to the bores 8 and terminate short of the lower face 10 of said body. Slots

11, substantially equal in depth to the depth of the bores 9 and having substantially parallel walls 12 and 13, extend between and open into the bores 8 and 9, while relatively small bores 14 extend upwardly from the lower face of the body 3 to the slots 11 and are preferably parallel to

the bores 8. Likewise the upper body 2 has a bore 15 that extends downwardly from the upper face of the body in substantially parallel relation to the bore 5 and terminates short of the lower face of the body. A slot 16 substantially equal in depth to the depth of the bore 15 and having substantially parallel walls 17 and 18 respectively extends between and opens into the bores 5 and

15, while a relatively small bore 19 extends upwardly from the lower face of the body 2 to the slot 16. As shown, this bore 19 is parallel to the bore 5 and is in alignment with a bore 20 of

similar diameter extending vertically through the lower body 3.

Located within the bores 9 and 15 are levers 22, coil springs 23 and sleeves or bushings 24 similar to parts 14, 20 and 21 respectively illustrated in my pending application aforesaid and constituting the means for retaining the shanks 26 of punches

25 within the bores 5, 7 and 8 respectively in the bodies. As shown, the levers 22 have spherical lower ends 27 journaled in rounded portions 28 and 29 respectively of the bodies 2 and 3 at the lower ends of the bores 9 and 15, extend diagonally through the slots 11 and 16 respectively and have arcuate upper ends 30 for engagement with the punch shanks 25. The spring bushings 24 are fixed within the bores 9 and 15 respectively so as to hold the spherical ends 27 of the levers within the rounded portions 28 and 29 respec-

tively, and the coil springs 23 extend between the sleeves 24 and levers 22 and normally hold the latter in operative tool engaging position.

In use, short punches 40 are held in the lower body 3 while a relatively long punch 41 is held in the upper body 2. Preferably the shanks 42 of the punches 40 have longitudinally extending arcuate slots or grooves 44 that are engaged by the arcuate ends 30 of the levers in the lower body 3 when the shanks 42 are inserted into the bores 8, while the shank 45 of the long punch 41 is provided adjacent its upper end with an arcuate slot or groove 46 that is engaged by the arcuate end 30 of the lever in the upper body 2 when said shank 45 is inserted into the aligned bores 7 and 5. In this connection it will be noted that the levers have a propping action and hold the upper ends of the punch shanks 42 and 45 respectively against the backing plates 2 and 6. Any suitable means such as an extractor pin 47 may be inserted into the bore 14 or into the aligned bores 19 and 20 to push the levers upwardly against the tension of the springs to release the punches so that they may be withdrawn from the holder. Thus punches may be readily inserted in or withdrawn from the holder without having to take it apart or separate it from the ram.

In Figures 6 to 8 inclusive I have illustrated a slight modification wherein the bodies 50 and 51 respectively are rectangular in shape and each contains a plurality of punch shanks. As shown, the upper body 51 has four bores 52 arranged in a row, while the lower body 50 has four bores 53 arranged in registration with the bores 52 in the upper body and is provided upon opposite sides of said bores 53 with two rows of bores 54. The spring pressed levers 55 correspond to the levers 22 and are located in bores 56 and 57 respectively at the sides of the bores 52 and 54 for retaining engagement with the tool shanks 58 and 59 respectively. Likewise bores 60 are provided in the lower body 50 in alignment with the bores 57 for receiving the extractor pins (not shown) and registering extractor pin bores 61 and 62 respectively are provided in the bodies 50 and 51 in alignment with the bores 56.

While it is believed that from the foregoing description the nature and advantages of the invention will be readily apparent, I desire, to have it understood that I do not limit myself to what is herein shown and described and that such changes may be resorted to when desired as fall within the scope of what is claimed.

What I claim as my invention is:

1. A tool holder having two sections arranged one on top of the other and provided with aligned bores for receiving a relatively long tool shank, the lower section having bores arranged about one of said aligned bores and adapted to receive shorter tool shanks, and means for retaining the shanks in the holder, including means in the upper section above the last mentioned bores for engagement with the long shank in the aligned bores, and other tool retaining means in the lower section in operative association with the shorter tool shanks.

2. A tool holder having two sections arranged one on top of the other and provided with aligned bores into which and from which a relatively long tool shank may be moved from a point below the lower section, the lower section having bores substantially parallel to one of said aligned bores for receiving shorter tool shanks, the last mentioned bores extending to and being closed by the

upper section whereby the latter may serve as a seat or abutment for said shorter shanks.

3. A tool holder having two separable bodies arranged in superposed relation and provided with aligned bores for receiving a tool shank, the uppermost body having means at one side of the bore therein for receiving tool shank retaining means, said bodies having aligned bores for receiving an actuating tool for such retaining means, the lower body having a plurality of bores extending from the bottom to the top thereof for receiving shorter tool shanks, said last mentioned bores being closed by the uppermost body so that the latter serves as a backing plate for shanks in the last mentioned bores, and the lower body having means at the sides of the bores therein for receiving tool shank retaining means and being provided with bores for receiving actuating means for such tool retaining means.

4. A tool holder having three separable sections arranged one on top of the other, the lower section having a plurality of bores extending upwardly from the bottom to the top thereof for receiving tool shanks, said bores being closed by the intermediate section whereby the intermediate section serves as a seat or abutment for the tool shanks received within the bores, the lower and intermediate sections having aligned bores extending from the bottom of the lower section to the top of the intermediate section for receiving a longer tool shank, the uppermost section extending over said aligned bores and serving as a seat or abutment for a tool shank received therein, and independent and automatically operable means in said lower and intermediate sections for retaining tool shanks in said bores.

5. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said retaining means being operable from a point below the lower body to release the shank in said registering bores.

6. A tool holder having a plurality of bodies arranged in superposed relation and having registering bores for receiving a tool shank, the lowermost body having other tool shank receiving bores, means in said lowermost body for holding the tool shanks in the last mentioned bores, and means in the other body for holding the tool shank that is received in said registering bores, the means in both bodies being operable from points below the lowermost body to release the tool shanks in said bores.

7. A tool holder having an upper face attachable to a ram of a punch press and having vertically extending means opening through the lower face of the holder and operable while the upper face is attached to permit the insertion upwardly into the holder through the lower face thereof of tool shanks of different lengths, and means for retaining the tool shanks in said holder, including means located in different horizontal planes in the holder but accessible and operable from points below the lower face thereof to permit the withdrawal of the tool shanks of different lengths through the lower face of the holder.

8. A tool holder having two tool receiving bodies arranged in superposed relation and having aligned bores constructed and arranged so

- that a tool shank may be received therein upon being moved upwardly in both bores, the lowermost body having bores constructed so that tool shanks may be received therein for engagement with the uppermost body while said bodies are in superposed relation, and means in said bodies for retaining the tool shanks in said bores and operable from the bottom of the lowermost body to release the tool shanks in said bores. 5 receive tool shanks of different lengths from points below the lowermost section, and means within the sections and operable automatically upon insertion therein of the tool shanks to engage and hold the same, said last mentioned means being accessible and operable from points below the lowermost section to release the tool shanks in the first mentioned means. 80
- 10 9. A tool holder having separable tool receiving sections arranged in superposed relation and having means operable while the sections are assembled for receiving tool shanks from points beneath the lowermost section, and means in said sections engageable with said shanks to retain the same in the holder, the retaining means in both sections being operable from points below the lowermost section to release the tool shanks in the holder. 90
- 15 10. A tool holder having separable sections arranged in superposed relation and having vertically extending means of different lengths opening through the lower face of the lowermost section and permitting the insertion into and withdrawal from said sections through the lower face 95 of the lowermost section while in superposed relation of tool shanks of different lengths, and means within said sections operable automatically to hold the tool shanks when inserted into said holder and operable manually from points below the lowermost section to release the tool shanks. 100
- 20 11. A tool holder having separable sections arranged in superposed relation and having means of different lengths extending upwardly from the lower face of the lowermost section and operable while the sections are in superposed relation to 105 115
- 25 12. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said bodies being provided with aligned bores that extend upwardly from the lower face of the lower body to the retaining means aforesaid so that a pin may be moved upwardly therein from points below the lowermost body to disengage the retaining means from the tool shank in said first mentioned aligned bores. 120
- 30 13. In combination, a retainer body having upper and lower sections, a punch having a long shank insertable upwardly into both sections from a point beneath the lower section, a punch having a shorter shank insertable upwardly into the lower section from a point beneath said section, said punches being independently removable without disturbing or separating said sections, and means operable upon insertion of said shanks into said sections to engage and hold said shanks. 125
- 35 14. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said bodies being provided with aligned bores that extend upwardly from the lower face of the lower body to the retaining means aforesaid so that a pin may be moved upwardly therein from points below the lowermost body to disengage the retaining means from the tool shank in said first mentioned aligned bores. 130
- 40 15. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said bodies being provided with aligned bores that extend upwardly from the lower face of the lower body to the retaining means aforesaid so that a pin may be moved upwardly therein from points below the lowermost body to disengage the retaining means from the tool shank in said first mentioned aligned bores. 135
- 45 16. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said bodies being provided with aligned bores that extend upwardly from the lower face of the lower body to the retaining means aforesaid so that a pin may be moved upwardly therein from points below the lowermost body to disengage the retaining means from the tool shank in said first mentioned aligned bores. 140
- 50 17. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said bodies being provided with aligned bores that extend upwardly from the lower face of the lower body to the retaining means aforesaid so that a pin may be moved upwardly therein from points below the lowermost body to disengage the retaining means from the tool shank in said first mentioned aligned bores. 145
- 55 18. A tool holder having upper and lower tool receiving bodies, the lower body being provided with a plurality of bores for receiving tool shanks, the upper body having a bore registering with one of the bores in the lower body, and serving as a backing plate for tool shanks in the other bores in the lower body, and means in the upper body for retaining a tool shank in said aligned bores, said bodies being provided with aligned bores that extend upwardly from the lower face of the lower body to the retaining means aforesaid so that a pin may be moved upwardly therein from points below the lowermost body to disengage the retaining means from the tool shank in said first mentioned aligned bores. 150
